UNITED STATES PATENT OFFICE.

ADOLF W. HERLING, OF CHICAGO, ILLINOIS.

VULCANIZING APPARATUS.

Application filed February 2, 1922. Serial No. 533,575.

To all whom it may concern:

Be it known that I, ADOLF W. HERLING, a citizen of the Republic of Poland, residing at Chicago, in the county of Cook and 5 State of Illinois, have invented certain new and useful Improvements in Vulcanizing Apparatus, of which the following is a specification.

This invention relates to improvements in 10 vulcanizing devices of the type commonly used for repairing the inner tubes of pneumatic tires.

The principal object of the invention is to 15 provide a pressing pad of such construction that the pressure will be uniformly distributed over that portion of the tube or other article which is being repaired.

Another object relates to the provision of 20 means whereby the workman may actuate and release the pressing means with his foot, leaving both hands free for the manipulation of the article being repaired.

Other objects relate to features of arrangement and construction which will appear more fully hereinafter, taken in connection with the accompanying drawings, wherein—

Figure 1 is a front elevation of my vulcanizer showing a battery of three vulcanizing devices, the intermediate device being provided with a circular and the others with a rectangular shaped pressing pad;

Fig. 2 is a side elevation of a single device;

Fig. 3 is a plan view of a circular pressing pad;

Fig. 4 is a sectional view of the same, taken on the line 3—3 of Fig. 3;

Fig. 5 is a plan view of a pad of rectangular shape.

Fig. 6 is a sectional view, taken on the line 5—5 of Fig. 5;

Fig. 7 is a plan view of the pedal and locking arrangement shown in Figs. 1 and 45 2; and

Fig. 8 is a detail view of a socket.

Similar reference characters are used throughout the drawings to indicate like elements, wherein—

50 10 is a table, bench, or other suitable support, having brackets 11 extending out-

wardly and upwardly from the side thereof supporting a steam box or curing plate 12, and having a pipe 13 leading thereto from a boiler or other source of supply of heat. 55

A bracket 14 is secured to the table, and pivoted on the shaft 15 thereof is the pressing lever 16, said lever being retained thereon by a cotter pin 17 or the like. The upper end of the pressing lever has a socket 60 18 formed therein, adapted to receive the stem 19 of the pressure pad 20, said socket portion preferably being split, as shown in Fig. 8, and having lugs 18^a thereon carrying a screw 18^b, whereby the socket may be 65 contracted to engage tightly the stem 19.

The pressure pad 20 may be made circular or rectangular in shape, as shown in Figs. 3 and 6, respectively. The circular pad (see Figs. 3 and 4 and the second device of Fig. 70 1) consists of a sheet metal or steel plate 21, having an upstanding flange 21^a and a hood 22 formed of alternate layers of fabric and rubber, suitably vulcanized, overlying said flange and secured thereon by a retaining 75 band 23 having flanges 23^a, said flanges carrying a bolt 24, or other tightening means, whereby an air-tight connection can be made between the flange 21^a and the hood 22. A valve 25 is secured in the plate 21, 80 whereby the pad may be inflated to a desired pressure. The lower end of the lever 16 extends under the bench 10, as shown, and is provided with screw-threaded holes adapted to receive threaded hooks 26 and 27. The 85 hook 26 engages a spring 28, which is secured at its other end to the table by a hook 29, or other means. The tension of the spring is such that the pad 20 will be carried away from the steam box 12 when 90 not in use.

When desired, the tension of the spring 28 may be varied by adjusting the threaded hook 26, as will be clear. A spring 30, 95 which is heavier than the spring 28, is engaged at its upper end by the adjustable hook 27, and at its lower end is secured by a hook 31, or other means, to a pedal 32 which is pivoted to a block 33, secured to the floor of the shop. On the under side of 100 the pedal are two depending lugs 34 and 35, each having a hole therein adapted to re-

ceive and guide the latch bolt 36. A pin 36^a extends laterally through the bolt, and between said pin and the lug 34 a spring 37 is retained, said spring tending to force the bolt to the right, as viewed in Fig. 2.

The rear end of the bolt 36 is pivoted to link 36^b, which in turn is pivoted to the releasing pedal 38, which is pivotally secured by a pin 39 to pedal 32 and is movable in slot 40 provided therein. The outer end of the bolt is bevelled, and is adapted to engage a catch 41 secured to the floor when the pedal 32 is sufficiently depressed.

In use my device operates as follows;

- 15 The steam box or curing plate 12 being at the correct temperature and the pad 20 suitably inflated, the workman adjusts the tube or other article to be vulcanized on the pad and depresses the pedal 32, which, through 20 the medium of spring 30, pulls the rear end of the lever 16 downwardly against the action of the spring 28. The pad, carrying the tube to be repaired, is then forced against the steam box 12, and is retained there- 25 against by means of the locking mechanism carried by the pedal. The pneumatic pad, as will be clear, effects a substantially uniform pressure against the steam box of the article being repaired, irrespective of ir- 30 regularities therein. It will be observed also that, due to the position of the steam box 12 with respect to the table 10, the tube will hang freely from the pad 20, thus rendering the adjustment of the tube more simple than 35 in many present devices.

When the vulcanizing operation is complete the operator presses the releasing pedal 38, which retracts the bolt 36 from engagement with the catch 41, whereupon spring 28 40 will move the pad away from the steam box, as will be obvious.

To adapt my device to a variety of repair work, I provide also pneumatic pads of rectangular shape, one of which is shown in 45 Figs. 5 and 6, these pads being readily interchangeable with the pad previously described. In the rectangular form of pad I provide a plate 45, of the desired shape, carrying a valve 25, as in the circular form. 50 A hood 46 is secured to the plate 45 by a frame 47 which extends around the plate, as shown, the edge of the hood material being tightly secured between said frame and said plate by means of rivets, screws, or other 55 means.

Although I have shown and described certain forms of my invention for purposes of illustration, I do not wish to be restricted thereto unduly, except where limitations 60 appear in the appended claims.

I claim:—

1. In a device of the class described, a lever, pressing means carried thereby, and foot operable means resiliently connected with said lever and adapted to actuate the same.

2. In a device of the class described, a curing plate, a pneumatic pad adapted to press the article to be repaired against said plate, foot operable means adapted to secure said pad in pressing position, and means carried by said foot operable means for releasing the same. 70

3. In a device of the class described, a curing plate, a pneumatic pad adapted to press the article to be repaired against said plate, 75 foot operable means adapted to secure said pad in pressing position, and foot operable releasing means adapted to release said last named means.

4. In a device of the class described, a curing plate, a pneumatic pad adapted to press the article to be repaired against said plate, foot operable means adapted to secure said pad in pressing position, and foot operable releasing means carried by and adapted to 80 release said securing means.

5. In a device of the class described, a curing plate, a pivoted lever, a pedal, a spring connecting said pedal with said lever, a pressing pad carried by said lever and adapted to contact with said plate upon the depression of said pedal. 90

6. In a device of the class described, a support, upwardly and laterally extending arms secured thereto, a heating plate carried by 95 said arms, a lever, and a pressing pad carried thereby and adapted to contact with said plate upon proper actuation of said lever.

7. In a device of the class described, a curing plate, a lever, a pneumatic pad carried thereby, a resilient means urging said pad away from said plate, a pedal, and a second resilient means transmitting motion from said pedal to said lever, whereby said pad is forced into contact with said plate. 100

8. In a device of the class described, a lever, a pneumatic pad carried thereby, and foot operable means resiliently connected with said lever and adapted to actuate the same. 105

9. In a device of the class described, a lever, a resilient pad carried thereby, foot operable means resiliently connected with said lever, and spring-actuated locking means carried by said other means. 110

10. In a device of the class described, a lever, pressing means carried thereby, foot operable means resiliently connected with said lever, locking means adapted to secure said foot operable means in depressed position, and spring-resisted means adapted to release said locking means. 120

11. In a device of the class described, a curing plate, a lever, a pressing member carried thereby and movable into contact with said plate, means comprising a spring adapted to actuate said lever, and resilient means resisting said actuating means. 125

12. In a device of the class described, a pressing pad comprising a base and a flexible 130

hood secured thereto adjacent the lateral edges thereof.

13. A pneumatic pad comprising a base, a flexible hood, means for forming an air-tight connection between said base and hood, 5 and a valve permitting the inflation of said pad.

14. A pneumatic pad comprising a base, a flexible hood, and a band secured to said base and pressing said hood adjacent its edge 10 into air-tight contact with said base.

In testimony whereof, I have subscribed my name.

ADOLF W. HERLING.
